TENSIONING STRAP FOR A TRAMPOLINE OR SIMILAR ARTICLE

Joseph H. Bohrer, Sr., Erie, Pa.

Application July 31, 1957, Serial No. 47,172

Term of patent 14 years

(Cl. D34—5)

FIG. 1

FIG. 2

FIG. 3

Fig. 1 is a side elevational view of a tensioning strap for a trampoline or similar article showing my new design;

Fig. 2 is a side elevational view to a larger scale, the opposite side being substantially a mirror image thereof; and

Fig. 3 is a top plan view thereof to an enlarged scale.

The broken fragmentary line showing of a sheet of flexible material and a trampoline frame in Fig. 1 is for illustrative purposes only.

I claim:

The ornamental design for a tensioning strap for a trampoline or similar article, as shown and described.
